RIBBON-PRINTING ATTACHMENT FOR PRESSES.

Application filed July 23, 1924. Serial No. 727,649.

This invention has to do with devices applicable to printing presses of various different kinds; and although the invention is here described as being in the form of an attachment for a printing press of a particular kind, yet it will be readily understood that the invention need not be in the form of an attachment; as ordinarily understood, but may be of course built integrally with the other parts of the press to make a complete integral press including the present invention; and also that the invention is not necessarily restricted, at least in its broader aspect, to a press of the particular kind herein described. However, in order to explain the invention as fully as possible it is explained as applied to that particular kind of press known as the Miller high speed press.

There are various objects of the invention, chief among which is provision of a mechanism that will enable a printing press to turn out at high speed a printed product after the style and general characteristics of a typewritten sheet. Or, in other words, a general object might be stated to be to make it possible to turn out work of the general kind and character turned out by a multigraph, but to produce such work at much higher speed and in more faithful imitation of a typewritten sheet where the impression takes place through the ink ribbon. There are various other objects and corresponding accomplishments of the invention but they will be best understood from the following description and accompanying drawings in which:

Fig. 1 is a vertical longitudinal section showing a printing press with the device of the present invention applied to it;

Fig. 2 is a plan of the same;

Fig. 3 is a side elevation, more or less diagrammatic, of the same;

Fig. 4 is an enlarged fragmentary plan taken as indicated by line 4-4 on Fig. 1;

Fig. 5 is an elevation taken on line 5-5 of Fig. 4;

Fig. 6 is an end elevation taken as indicated by line 6-6 on Fig. 4; and

Fig. 7 is a detailed elevation taken as indicated by line 7-7 on Fig. 4.

By reference to the drawings the structure and operation of the illustrated press will be described in so far as the operations

of that particular type of press are necessary to be understood in order to give a complete description of the improvements embodying the present invention. It will be understood, however, that the invention is not limited to the particular structure and operation of the particular type of press selected for the purpose of this description. Such a press as herein illustrated has a bed 10 that is reciprocated in one direction through the action of certain cam operations 65 and is reciprocated in the opposite direction by being moved into gear connection with cylinder 11, this cylinder being positively rotated at all times, in the direction indicated by the arrow in Fig. 1, by the gearing 65 train 12, 13, 14, 15 illustrated in Fig. 3. At the same time the arrangements are such that the cylinder itself, in addition to its continuous rotary motion, is reciprocated by the action of cams 16 operating on pivoted 75 cam follower 17 which in turn through arm 18 and connecting rod 19 reciprocates the bearings 20 in which the cylinder is journaled. Cams 16 are mounted on what may be termed the main shaft 21, which is continuously rotated. Driving gear 13 is also mounted on this main shaft, and the gear train 14, 15, derives its rotation from the cam shaft gear 18. The bed 10 is moved toward the right in Fig. 1 by the action of cam 21a on roller 22, the motion of the roller being transmitted through connecting rod 23, bell crank lever 24 and connecting rod 25 to the bed. During this motion to the right the bed travels in a plane of movement 85 below the position shown in Fig. 1, low enough to keep the bed rack 26 out of engagement with the cylinder gear 27. At the end of its movement to the right the bed is raised to the level shown in Fig. 1 so 90 that the rack and gear intermesh and then the travel of the bed to the left is caused by this gear connection with the constantly rotating cylinder. Reaching the left hand end of its movement the bed is again dropped and again moved toward the right. The vertical movement of the bed is effected by 95 vertically moving plungers 30 connected to the ways 31 in which the bed rides, the lower ends of these plungers being operated 100 upon by eccentrics or cams 32 which in turn are operated, through the medium of connecting rods and toggles 33, 34, and 35 from

a pivoted arm 36 carrying a roller 37 that is operated by cam 38. It will be unnecessary to describe in detail all of the various interactions and relative timings of the various parts, as enough has now been described to enable the present invention to be understood. It will suffice to say that the timing of the various movements is such that, as the cylinder and bed reach the left hand end of their reciprocating movement in Fig. 1 the feeder (not illustrated) feeds a sheet or sheets of paper 40 to the cylinder, and these are gripped by suitable cylinder grippers, indicated at 41. The previous sheet or sheets have just been discharged onto the delivery mechanism, which need not be illustrated or described. On the subsequent movement of the cylinder and plate toward the right the sheets are carried around the cylinder until, when the cylinder reaches its right hand position the forward edge is just ready to pass between the cylinder and bed. The bed is then raised and then, on the subsequent reciprocating movement of the cylinder toward the left, the cylinder also constantly rotating, a sheet is passed toward the left between the cylinder and bed, taking an impression from the type 42 on the bed. At the end of the left hand movement the bed drops, the cylinder keeps on rotating and delivers the printed sheet to the delivery mechanism and takes the next sheet from the feeder.

In a press of the general character just described the present invention is applied in the manner that will now be made clear. A frame 45 is attached to the reciprocating bed, and this frame may either be regarded as an attachment to the bed or as a part of the reciprocating bed. It may be constructed in any manner desired; in attaching the present invention to a press already constructed it is found convenient to form this frame 45 of bars or the like. This frame 45 extends out far enough at each end of the bed so that the two ribbon spools 46 which are carried in bearings 47 on frame 45 will not strike any of the stationary parts of the press during their movements with the bed. The ribbon 48 may be either of a single width to cover the entire bed width or the ribbon may be made up of a plurality of widths. Thus, for instance, where the press is arranged to take a two letter size sheet at a time it may be desirable to make the ribbon in two widths as illustrated. The ribbon winds up at each end on the two ribbon spools 46; and between the ribbon spools the ribbon passes over the bed from end to end, suitable stationary rollers being provided at 49 to carry the ribbon over the inking rolls 50 and to carry the ribbon down close to the bed during that part of the ribbon travel where it passes under the cylinder. It will be noted that, by virtue of

the position of the ribbon with reference to the bed and cylinder, the paper in traveling around the cylinder is above the ribbon while the ribbon is above the type, so that the ribbon comes between the paper and the type. The action of the cylinder, as will be well understood, is to roll the paper over the type and ribbon on the bed, there being no relative movement longitudinally of the bed, between the paper and the type and bed during the impression stroke of the press. Likewise it will be seen that there is no longitudinal movement of the ribbon relative to either the bed or the paper, because the ribbon is carried by the bed itself in its movements. Thus, during the impression stroke of the press the ribbon is stationary relative to the bed while the cylinder, relative to the bed, rolls the paper, in impression, over the ribbon over the type.

Although the ribbon remains stationary relative to the bed during each printing stroke, the ribbon is advanced step by step during each back stroke when the bed is dropped away from the cylinder. The amount of movement on each stroke is comparatively small, but sufficient to present constantly a new impression surface on the ribbon to the type and the paper, so as to maintain even and uniform printing results. This advancement of the ribbon is caused by the mechanism shown in the drawings and shown more in detail in Figs. 4 and 7. It will be noted that each ribbon spool 46 carries a ratchet wheel 50^a; and preferably each spool carries two such ratchet wheels so that any spool may be used in a reversed end to end position. The spool bearings 47 are equipped with a quick releasing device 51 so that new spools of ribbon may be substituted when necessary. The devices that actuate ratchets 50^a at each end of the platen stroke may conveniently be mounted on any suitable frames or supports. In the present instance they are mounted on supports 55 and 56 which are in the particular press illustrated, the supports for the feeder and receiving tray respectively. On these supports are mounted suitable bearings that carry a small shaft 57 and on the end of the shaft a pawl 58 is carried in such a position that, as the bed comes to either end of its movement one of the ratchet wheels engages this pawl and, throwing the pawl down and back around the shaft 57 (see the dotted line position in Fig. 6) causes the ratchet wheel and the corresponding spool to be rotated through an angle that will depend upon the position of the pawl at the time it is engaged by the ratchet. In order to vary this engagement position of the pawl there is provided a small pivoted arm 60 whose free end is in such a position as to be engaged by the roll of ribbon on the spool and to be moved in the directions indi-

cated by the arrows in Figs. 2 and 4 by the reciprocating motion of the spool as the spool comes to the end of its stroke. The amount at which this arm 60 is moved will 5 of course depend upon how full the spool is, the movement being just in proportion as the spool is more nearly filled. The other end 61 of this pivoted arm lies behind the small arm 62 projecting up from shaft 57. 10 Consequently, movement of arm 60 in the direction indicated by the arrow will move shaft 57 in such a direction as to move pawl 58 from the full line position shown in Fig. 6 toward the dotted line position shown in 15 that figure. The arrangements of the various parts are such that although the roll of ribbon contacts with arm 60 before ratchet 50 moves onto pawl 58, the ratchet will at some point, in its movement toward the 20 pawl, strike the pawl, and from that point on the engagement of the pawl with the ratchet will move the pawl and move the ratchet wheel around. But the exact point at which the ratchet wheel engages the pawl 25 is controlled, as before explained, by the amount of movement given arm 60, and that in turn depends upon the size of ribbon roll on the spool. By this arrangement the movement of the ribbon at the end of the 30 stroke is kept uniform, in spite of the varying size of the ribbon roll.

It will of course, be understood that only one of the ribbon advancing devices is in 35 operation at a time, the ribbon being advanced step by step in one direction until it is entirely wound up on one spool; and then the ratchet devices at that end are put out of operation and the ones at the other end are thrown into operation, when the ribbon 40 begins to be advanced step by step in the other direction. But in either case it will be seen that the advancement of the ribbon takes place just before the end of the stroke in one direction or the other. Where the advancement takes place before the end of the stroke toward the right in Fig. 1 it of 45 course takes place before the bed rises and clamps the ribbon between the bed and cylinder. In a case where the ribbon movement takes place near the left hand end of the stroke, it also takes place after the bed has begun to drop which it begins to do just before the end of its stroke toward the left and thus the advancement of the ribbon 55 in that direction takes place after the ribbon is freed between the bed and cylinder.

Small friction members are provided as indicated at 65; to press against a ratchet of each ribbon spool so as to keep a certain tension on the ribbon and prevent it from becoming slack at any time.

Ink is applied to the type on the bed in the usual manner; that is, the ink is applied directly to the type and not to the ribbon. The ink distributed over the type is trans-

ferred to the ribbon by the contact of the ribbon with the type during the printing stroke. The ribbon is preferably of a fabric that is suitably pervious to the ink used, and the ink thus gradually permeates the 70 ribbon and works through to the upper face. After a ribbon has become sufficiently permeated with ink it will then produce a practically perfect uniformity of printing onto the paper, and will continue to do so. Ink 75 is of course being continuously supplied to the under surface of the ribbon uniformly throughout its length; and is correspondingly being constantly used from the upper surface of the ribbon uniformly throughout 80 its length. The intermittent but uniform movement of the ribbon over the bed, and the uniform supply of ink from the type to the ribbon, accomplish these results.

Having described a preferred form of my 85 invention, I claim:—

1. In a printing press having a type carrying member and an impression member movable relatively to and from each other, an ink pervious ribbon passing between said members and adapted to lie between the type and the papers to be printed on, means to supply ink to the type, and means to move the ribbon step by step during successive periods when the two members are moved away from each other; the ribbon being carried by the type carrying member; and said ribbon moving means embodying a spool on which the ribbon is wound, ratchet means operated by virtue of the movement of the ribbon with the type carrying member to rotate the spool step by step, and means controlled by the amount of ribbon on the spool to govern the amount of rotation imparted to the spool by the ratchet means. 95

2. In a printing press having a reciprocating type carrying bed and a revolving cylinder to press a sheet toward the type on the bed, an ink pervious ribbon passing between the type and the sheet and carried by the reciprocating bed, means to move the ribbon step by step relative to the bed, said means embodying a spool carried by the bed, ratchet means to rotate the spool operated by virtue of the movement of the bed and spool, and means controlled by the amount of ribbon on the spool to govern the amount of rotation imparted to the spool by the ratchet means. 100

3. In a printing press having a flat type carrying member and a rotary impression member, the type carrying member being reciprocable in its own plane and the two members being relatively movable in a direction transverse of the type carrying member to separate the two members during reciprocation of the type carrying member in one direction; an ink pervious ribbon extending lengthwise of the type carrying member and between it and the impression member, rib- 115 120 125 130

bon carrying spools carried on the ends of the type carrying member, the ribbon extending between the spools and reciprocating with the type carrying member, means to 5 rotate the ribbon spools by virtue of their reciprocation with the type carrying member, means at one side of the impression member to space the ribbon from the type

carrying member, and means operating in the space between the ribbon and type carrying member to apply ink direction to the type carried by said member.

In witness that I claim the foregoing I have hereunto subscribed my name this 17 day of July, 1924.

GUY V. NEWTON.
